US00D785175S

(12) **United States Design Patent** (10) **Patent No.:** **US D785,175 S**
(45) **Date of Patent:** **** Apr. 25, 2017**

(54) **TROCAR NEEDLE**

(71) Applicant: **Guangzhou T.K Medical Instrument Co., Ltd.**, Guangzhou (CN)

(72) Inventors: **Xing Zhou**, Guangzhou (CN);
Shaoming Zhu, Guangzhou (CN);
Linhai Liu, Guangzhou (CN); **Jiajiang Wei**, Guangzhou (CN); **Huaping Xu**, Guangzhou (CN); **Lifei Luo**, Guangzhou (CN)

(73) Assignee: **GUANGZHOU T. K. MEDICAL INSTRUMENT CO., LTD.**, Guangzhou (CN)

(**) Term: **15 Years**

(21) Appl. No.: **29/528,986**

(22) Filed: **Jun. 2, 2015**

(30) **Foreign Application Priority Data**

Mar. 19, 2015 (CN) 2015 3 0067286

(57) **CLAIM**

The ornamental design for a trocar needle, as shown and described.

DESCRIPTION

FIG. 1 is a perspective view of a trocar needle;
FIG. 2 is a first side view of the design of FIG. 1;
FIG. 3 is a second side view of the design of FIG. 1;
FIG. 4 is a third side view of the design of FIG. 1;
FIG. 5 is a fourth side view of the design of FIG. 1;
FIG. 6 is a top view of the design of FIG. 1; and,
FIG. 7 is a bottom view of the design of FIG. 1.

The broken lines shown in the drawings represent portions of the trocar needle that form no part of the claimed design.

1 Claim, 6 Drawing Sheets
